UNITED STATES PATENT OFFICE.

CHARLES L. ROWLAND, OF BROOKLYN, NEW YORK.

DESIGN FOR A MOUTH-PIECE FOR GAS-RETORTS.

SPECIFICATION forming part of Design No. 21,435, dated March 29, 1892.

Application filed February 23, 1892. Serial No. 422,591. Term of patent 14 years.

To all whom it may concern:

Be it known that I, CHARLES L. ROWLAND, a citizen of the United States, residing at Brooklyn, in the county of Kings and State of New York, have invented and produced a new and original Design for Mouth-Pieces for Horizontal Gas-Retorts, of which the following is a specification, reference being had to the accompanying drawings.

Figure 1 is a perspective view of a retort mouth-piece embodying my design. Fig. 2 is a rear elevation of the same, and Fig. 3 a side view.

The design consists in a structure of tubular form, flanged at both openings and shaped in the peculiar manner illustrated in the drawings—that is to say, the rear of the mouth-piece is a D-shaped opening, the bottom being flat or straight and the sides and top curved somewhat after the manner of the capital letter "D." This opening is surrounded by a flange A, the contour of which conforms to the contour of the opening. The walls which extend forward from this rear opening are shaped as follows: The bottom B is flat;

but the sides C C are convergent, so that the front opening to mouth-piece is narrower than the rear opening. The walls C' C', extending upwardly from the side walls C C, are also convergent, so that while the D shape of both openings is preserved the front opening is smaller than the rear one. The front opening is surrounded by a flange D, the contour of which conforms to the contour of the opening except at the sides. Projecting lugs d d are formed on the flange. In the top wall of the retort, between the front and rear flanges A D, is a tubular hub E.

The essential feature of my design consists in the general shape or contour of the mouth-piece above described.

What I claim as my invention is—
The design for a gas-retort mouth-piece, herein shown and described.

In testimony whereof I have hereunto subscribed my name.

CHARLES L. ROWLAND.
